F. J. PLYM

DOOR

Filed Jan. 26, 1926

UNITED STATES PATENT OFFICE.

FRANCIS J. PLYM, OF NILES, MICHIGAN, ASSIGNOR TO THE KAWNEER COMPANY, OF NILES, MICHIGAN, A CORPORATION OF MICHIGAN.

DOOR.

Application filed January 26, 1928. Serial No. 83,850.

The present invention relates to certain new and useful improvements in metal doors in which the construction is simplified and made possible at a lower cost without diminishing the strength, attractiveness or efficiency of the door. Among the further objects of my invention are the following:

To provide a door formed mainly of channel members rather than of tubular construction so that there is a greater facility in manufacture.

To afford a door of metal which when once fit will not warp, twist or get out of shape.

To create a door having a kick plate at the bottom to aid in opening the door, protect the bottom of the same and so arranged as to reinforce the entire unit.

To provide a door which may have just enough wood or the like in the channel members to deaden the metallic sound if desired.

To provide a door constructed of channel members so that the frame may be thinner and narrower and thus permit of more center area.

A further object is to provide a door having channel members so arranged as to materially increase the stiffness and rigidity of the door, and provide a door which in practice will not weaken or unduly flex; and such other objects, advantages and capabilities as will later more fully appear.

While I have shown in the accompanying drawings a preferred embodiment of my invention, I wish it understood that the same is susceptible of modification and change without departing from the spirit of my invention.

Referring to the drawings,

Fig. 1 is a vertical transverse section taken on line 1—1 of Fig. 2 and partly broken away.

Fig. 2 is a front elevation of a door embodying my invention.

Fig. 3 is a fragmentary section on line 3—3 of Fig. 2.

Fig. 4 is a vertical transverse section of a channel member open at the bottom.

Fig. 5 is a reproduction of Fig. 4 without the filler.

My invention more in detail comprises a door having a top rail 1, a bottom rail 2 and side rails 3 and 4. The top rail 1 has a metal channel member 5 which may open outwardly or inwardly as desired as shown

in Figs. 1 and 4. A wood filler or the like 6 may if desired be placed in said channel member, the wood being exposed at the top or bottom. The bottom rail 2 has a channel member 5 which may open either downwardly or upwardly and contains wood filler member 6. The channel member 5 of the bottom rail 2 may extend downwardly a short distance beyond the wood filler 6 if desired as clearly shown in Fig. 1 at 8. The side rails 3 and 4 are formed of channel members 5 which open inwardly so that the metal forming the closed side of the channel is exposed on the side edges of the side rails 3 and 4 as clearly shown in Fig. 3. These channel members 5 of the side rails 3 and 4 may also have a wood filler 6' or the like which may be slightly different in shape than the fillers of the upper rail 1 and the lower rail 2, as clearly shown in Fig. 3. A kick plate 9 is secured to the bottom of the door by rivets or the like 10 as clearly shown in Fig. 1. Gripping or panel retaining members 11 joined to the channel members 5 hold the glass panel or other center filling 80 material 12 in place. Bolts or the like 13 may be used for clamping the gripping members 11. It will be seen in use that with the channel members of this invention, thinner and narrower top, bottom and side rails may be used, thus permitting of more glass or center panelling area. It was heretofore necessary to use very heavy bottom, top and side members in order to hold the large center glass or paneled portion or portions 85 safely and rigidly in position. By this invention I have eliminated these disadvantages and have produced a metal door made up of channel members instead of closed tubing, thus reducing the cost of production, without lessening the stiffness and rigidity of the door.

Having now described my invention, I claim:

1. A door comprising a framework made up of metal channel members, the top and bottom channel members open on one end, and the vertical side channel members opening inwardly with the closed edges of the same forming the two vertical edges of the door, an intermediate horizontal channel member spaced from the bottom channel member, and a kick plate secured to the intermediate channel member and the bottom channel member, said kick plate com- 100

110

prising a pair of sheet metal plates connecting the outer faces of the intermediate and bottom channel members.

2. A door comprising a framework made up of metal channel members, the top and bottom channel members open on one end and the vertical side channel members opening inwardly with the closed edges of the same forming the two vertical edges of the door, an intermediate horizontal channel member spaced from the bottom channel member, and a kick plate secured to the intermediate channel member and the bottom channel member and comprising a pair of sheet metal plates connecting their outer faces, and holding means associated with the top, intermediate and side channel members for retaining in position a panel member.

3. A door comprising top and bottom sheet-metal channel members each having an open side, side channel members of sheet metal and a cross sheet-metal channel member disposed apart from but relatively close to the bottom channel member, all of said channel members being united to form a rigid frame, the inner portions of said top and sides and the upper portion of said cross channel member having inwardly extending

supports and a panel mounted therein and extending substantially the full length of the door from the upper channel member to the cross channel member, and two sheet metal plates connecting the outside faces of said cross and bottom channel members and forming a metal kick plate for the outsides of the door bottom.

4. A door comprising top and bottom sheet-metal channel members of relatively narrow dimensions, each having an open side, side channel members of sheet-metal of relatively narrow dimensions, and a sheet-metal cross channel member disposed apart from but relatively close to the bottom channel member, all of said channel members being united to form a rigid frame, and a panel mounted between the top, sides and cross panel members and extending substantially the full length of the door, and sheet-metal plates substantially flush with and attached to the exterior faces of the cross and bottom channel members and forming a metallic kick plate and panel for the bottom of the door.

In witness whereof, I hereunto subscribe my name to this specification.

F. J. PLYM.
